CLAIM

The ornamental design for an telephone handset, as shown and described.

DESCRIPTION

FIG. 1 is a perspective view of a telephone handset;

FIG. 2 is a front elevational view thereof;

FIG. 3 is a rear elevational view thereof;

FIG. 4 is a left elevational view thereof;

FIG. 5 is a right elevational view thereof;

FIG. 6 is a top elevational view thereof; and,

FIG. 7 is a bottom elevational view thereof.

The broken line showings of FIG. 1 are for illustrative purposes only and form no part of the claimed design.
